UNITED STATES PATENT OFFICE

162,149

COMBINED GARDEN COUCH AND CLOTHESLINE RACK

Bert Gaither, Van Nuys, Calif.

Application February 23, 1950, Serial No. 8,209

Term of patent 14 years

(Cl. D5—4)

To all whom it may concern:

Be it known that I, Bert Gaither, a citizen of the United States, residing in Van Nuys, in the county of Los Angeles and State of California, have invented a new, original, and ornamental Design for a Combined Garden Couch and Clothesline Rack, of which the following is a specification, reference being had to the accompanying drawing, forming part thereof:

Fig. 1 is a top plan view of a combined garden couch and clothesline rack, showing my new design.

Fig. 2 is a front elevational view thereof.

Fig. 3 is a rear view.

Fig. 4 is an enlarged end view as seen from the left end of Fig. 2.

Fig. 5 is a similarly enlarged end view as seen from the right end of Fig. 2.

I claim:

The ornamental design for a combined garden couch and clothesline rack, substantially as shown.

BERT GAITHER.
